YERMIE G. STERN, OF NEW YORK, N. Y.

DESIGN FOR A DRESS

Application filed October 20, 1931. Serial No. 41,461. Term of patent 3½ years.

To all whom it may concern:

Be it known that I, YERMIE G. STERN, a citizen of the United States, residing at New York city, in the county of New York and State of New York, have invented a new, original, and ornamental Design for a Dress, of which the following is a specification, reference being had to the accompanying drawing, forming part thereof.

In the drawing:

The figure is a perspective view of a dress showing my new design. The back has the same general appearance as the front with the exception that the bodice is plain in the back and distinguished from the lacing thereof at the front.

I claim:

The ornamental design for a dress as shown and described.
